J. CUNNINGHAM

SHAFT HANDLE RETAINING MEANS

Filed Feb. 29, 1924

J. Cunningham
Inventor

By *Oliver O'Brien*
Attorney

UNITED STATES PATENT OFFICE.

JOSEPH CUNNINGHAM, OF GLEN CARBON, ILLINOIS.

SHAFT-HANDLE-RETAINING MEANS.

Application filed February 29, 1924. Serial No. 696,095.

To all whom it may concern:

Be it known that I, JOSEPH CUNNINGHAM, a citizen of the United States, residing at Glen Carbon, in the county of Madison and State of Illinois, have invented certain new and useful Improvements in Shaft-Handle-Retaining Means, of which the following is a specification.

This invention relates generally to crank shafts of any form of power machine and has more particular reference to a means whereby the hand crank that affords a means for manually turning said crank shaft may be positively retained thereon without the liability of the same slipping from the end of the shaft during the manual turning operation thereof.

In a great number of machines where a detachable crank handle is employed for manually rotating the shaft, it is generally the practice to employ a cotter key for retaining the handle upon the end of the shaft. It often times happens that the operator of the machine will overlook the practice of using said cotter key which will often times result in the crank handle slipping from the shaft and some times resulting in injury.

It is therefore the primary object of the present invention to provide a positive means for retaining handles upon the ends of crank shafts and this by the provision of simple and inexpensive means.

With the foregoing and other objects in view as the nature of the invention will be better understood, the same comprises the novel form, combination and arrangement of parts hereinafter more fully described, shown in the accompanying drawing and claimed.

In the drawing wherein like reference characters indicate corresponding parts throughout both of the views,

Figure 1 is an end view of a crank shaft partly in side elevation and partly in cross section, the same being equipped with my improved means for retaining the hand crank upon the end thereof, said hand crank being shown in dotted lines, and

Figure 2 is an elevational view of the end of the crank shaft that carries said hand crank retaining means.

Now having particular reference to the drawing, 5 indicates the crank shaft of any

form of power machine, and in this instance 55 the same is formed at its outer end with a tapered squared portion 6 that is formed with a longitudinal slot or pocket 7 and over which is adapted to be detachably engaged a well known form of crank turning 60 handle 8.

As a means for positively maintaining said crank handle 8 upon the tapered squared end 6 of said shaft 5 during the manual turning of said shaft through the medium 65 of this handle, there is disposed within said slot 7 a relatively elongated dog 9 pivoted within the front end of the slot through the medium of a set screw designated 10.

The forward end of this relatively elongated dog 9 is formed upon its outer edge with an extension 11 for providing adjacent the end of said dog, a shoulder 12.

Disposed within the slot 7 rearwardly of said dog 9 is a curved band spring 13 that 75 serves as a means for normally swinging the forward end of said dog 9 outwardly of the end of said slot 7 as shown in Figure 1. For limiting the outward swinging movement of this dog within said slot, the inner 80 end of the same is provided with an extension lug or finger 14 that is adapted to engage within a notch 15 formed at the inner end of said slot 7.

It will therefore be seen that upon an 85 application of the crank handle 8 to this squared and tapered end 6 of the shaft 5, said dog 6 will be forced into the slot 7 for allowing the positioning of the handle upon the shaft in the manner as shown in the 90 dotted lines of Figure 1. The shoulder 12 formed upon said dog will engage in back of the shaft engaging portion of the handle for positively preventing the accidental displacement of the handle with respect to the 95 shaft, and in the event that it is desired to remove the handle from the shaft, the dog may be swung inwardly by depressing with the thumb or forefinger, the projecting end of said dog.

It will thus be seen that I have provided a highly novel, efficient and simplified means for positively retaining hand cranks upon the ends of crank shafts, and even though I have herein shown and described the most 105 practical embodiment of the invention with which I am at this time familiar, it is nevertheless to be understood that minor changes

2
may be made therein without departing from the spirit and scope of the appended claim.

Having thus described my invention, 5 what I claim as new, and desire to secure by Letters Patent is:—

A device of the class described comprising a shaft tapered at its free end, said tapered portion being polygonal in cross section and 10 being formed in one flat face with a recess providing a pocket, the outer end of the recess being closed and disposed inwardly of the corresponding end of the shaft, said pocket being open only upon its top, there 15 being a notch formed at the opposite end of

the recess, a latch of a length substantially equal to the length of said pocket, a shaft extending crosswise of said pocket, said latch being pivoted at its inner end upon said shaft, said latch being formed at its 20 outer end with an angular extension providing a shoulder and having an extension at its inner end projecting into a notch provided at the adjacent end of said pocket, and a spring arranged in said pocket between the bottom of the same and said latch. 25

In testimony whereof I affix my signature

JOSEPH CUNNINGHAM.
